(57) **CLAIM**

The ornamental design for a barricade stop, as shown and described.

DESCRIPTION

FIG. 1 is a perspective view of a barricade stop showing my new design;

FIG. 2 is another perspective view of the barricade stop shown in FIG. 1;

FIG. 3 is a front elevational view of the barricade stop shown in FIG. 1;

FIG. 4 is a right side elevational view of the barricade stop shown in FIG. 1;

FIG. 5 is a rear elevational view of the barricade stop shown in FIG. 1;

FIG. 6 is a left side elevational view of the barricade stop shown in FIG. 1;

FIG. 7 is a top plan view of the barricade stop shown in FIG. 1; and,

FIG. 8 is a bottom plan view of the barricade stop shown in FIG. 1.

The broken lines shown in the Figures are included for the purpose of illustrating portions of the barricade stop that form no part of the claimed design.

1 Claim, 5 Drawing Sheets
